CAN SPRAYING MACHINE

John H. Murch, East Orange, N. J., assignor to
 American Can Company, New York, N. Y., a
 corporation of New Jersey

Application October 30, 1934, Serial No. 750,721

20 Claims. (Cl. 91—45)

The present invention relates to spraying machines and has particular reference to machines for spraying or coating interior surfaces of containers or cans with a liquid coating material which is sprayed on in a manner which builds up a coating in stages and on different sections of the surfaces so that an even and unbroken coated surface results.

An object of the invention is the provision of a can spraying machine wherein different sections of surfaces of cans to be coated are independently sprayed and the sectional coatings are then merged one into the other so that complete and thorough coverage of the desired surface is assured.

Another object is the provision of a spraying machine wherein open-end cans are rotated first in one direction and then in an opposite direction during the application of successive coats of material, this procedure insuring that the coating is applied to the inner corner of the can where the can bottom joins with the side wall and where the bottom surface coating merges with that of the sides so as to effectively coat this part of the can which is particularly vulnerable to coating imperfections by ordinary coating methods.

Another object is the provision, in such a machine, of a spraying mechanism which is particularly designed for effectively spraying the edges of inwardly projecting side seams of cans, cans of this type, that is those having a flush outside wall with the side seam on the inside, representing a large part of all interiorly coated cans.

Another object is the provision, in a can spraying machine, of means for carrying off the spray fumes and any excess spray material which is not applied to the can surfaces during the coating operations.

Numerous other objects and advantages of the invention will be apparent as it is better understood from the following description, which, taken in connection with the accompanying drawings, discloses a preferred embodiment thereof.

Referring to the drawings:

Figure 1 is a front elevation of the upper part of a can spray machine embodying the instant invention, parts being broken away;

Fig. 2 is a sectional plan view of the same taken substantially along the line 2—2 in Fig. 1;

Fig. 3 is a side elevation of the left side of the machine shown in Fig. 1;

Fig. 4 is a sectional plan view taken substantially along the broken line 4—4 in Fig. 3;

Fig. 5 is a transverse sectional view taken substantially along the line 5—5 in Fig. 3; and

Fig. 6 is a wiring diagram of an electric circuit utilized in the machine.

The cans to be coated are introduced into the apparatus by an inclined runway the machine end of which terminates adjacent the periphery of an intermittently rotatable can carrier or turret having can pockets into which the cans are individually delivered. Each can enters its turret pocket at a can receiving station A (Fig. 1).

The turret on its first step movement conveys the can first to an idle station B. On its second advancement it comes into a spraying station C and in that position its bottom end is located in front of a movable electro-magnetic chuck which is continuously rotated at a high speed. The chuck moves into engagement with the can bottom and magnetically picks up and holds the can which immediately starts revolving about its longitudinal axis. This is in a counter-clockwise direction as viewed from the front of the machine (Figs. 1 and 5).

The open or top end of the revolving can at this station is adjacent the discharge end of an oscillating spray head, which thereupon projects a jet or spray of liquid coating material into the can and against the interior surface of its bottom. The spray is first directed toward the outer edge of the bottom and particularly into the corner of the rotating can where its bottom wall joins with the side wall (see the dot and dash lines of Fig. 4) and is then moved toward the center of the can (full lines Fig. 4).

This corner is a section of the can which under ordinary coating methods may be insufficiently covered owing to the tendency of the coating material under capillary attraction and surface tension to pull across between bottom and side walls and leave an uncoated space or skip. This will be again referred to.

This spraying of the bottom continues for a desired number of revolutions of the can after which the spray is shut off leaving the inside of the can bottom covered with an even coating of material. The magnetic chuck then returns to its first position during which movement the can is stripped off by a stationary plate. It stops turning and rests in its turret pocket ready for the next step.

The turret next conveys the now partially coated can to a station D where it passes in between a second rotating electro-magnetic chuck and a reciprocating spray head. The chuck at station D is identical in construction and operation with the one at station C and engages and rotates the can in the same manner only this

time in an opposite or clockwise direction (Figs. 1 and 5).

At station D the open or top end of the can is in front of the discharge end of the spray head and this head now moves into the can. At its innermost position (Fig. 2) the coating material is ejected as a spray from the head and is directed at an angle into the joint or corner where can bottom and side walls join. The angular discharge of spray continues while the nozzle is drawn out of the can, the spray material striking against the interior side wall of the revolving can.

The spray material as it falls on the can is sufficiently thin to flow down along the moving wall and as the side seam passes the spray jet several times the coating is directly applied to and flows along the upper edge of the seam and into the interstices between seam and can wall, as well as over the entire surface of the side seam. This is another can section which when coated by ordinary methods is likely to be improperly covered owing to the tendency of coating material under capillary attraction and surface tension to span across the groove alongside of the seam. This will be further explained in the following description.

As the withdrawing spray end of the head reaches the outer flanged end of the can, the spray is cut off but some of the material flows out and covers the flange itself. The spray fumes and any excess spray not applied to the can surfaces at this place are carried off through an exhaust duct. As before the can is stripped from the chuck, stops its rotation and rests within the turret pocket ready for its next advancement.

The moving turret now carries the can to a station E where it passes between a third rotating magnetic chuck and a second reciprocating spray head. Again the can is engaged and rotated by the magnetic chuck only this time the can turns in a counter-clockwise direction (Figs. 1 and 5). The same type of spraying action is here repeated as the spray head moves in and out, the coating material being deposited directly over the still moist former coating. Gravity, acting on the applied coating which flows down as the can wall moves in its opposite direction, brings the material against the opposite edge of the side seam and again into all interstices between seam and side walls.

The same can being thus rotated in opposite directions at different stations receives its coating material in a manner which is particularly effective for covering both longitudinal edges as well as the inner or top face of the side seam and well into the interstices along both edges of the side seam where it joins with the can wall. Thus the interior surface of the bottom, the full interior surface of the side walls including the side seam and the inside of the flange at the open end of the can are all evenly coated. The corner or junction of the bottom and side wall receives three separate overlapping applications of the coating material which insures the proper covering of this important and vulnerable part of the can.

A preferred form of apparatus which is disclosed in the drawings comprises in part a turret 11 (Figs. 1, 2, 3 and 4) composed of a pair of spaced parallel discs 12 which are mounted on a horizontal shaft 13. The shaft is intermittently rotated in any suitable manner and is carried in a bearing 14 formed in a main frame 15 which

is the main support for the various working parts of the machine.

Cans a having a bottom end b and an inwardly projected side seam c (Fig. 5) are brought into the top of the machine and into the can receiving station A, these cans rolling in a continuous procession along an inclined runway 16 (Figs. 1 and 3). The runway comprises spaced and parallel can guides 17 having their lower or machine ends secured to brackets 18 which in turn are bolted to the top of the machine frame 15. This end of the runway terminates adjacent the periphery of the turret 11 and the lowermost can in the runway rests on or in the turret holding the other cans back.

The turret discs 12 are formed with can pockets 21 and at each rest period of the turret a can pocket is brought into can receiving position (station A) and the lowermost can a in the runway drops into the pocket. On the next step 20 rotation of the turret this can is advanced to the idle station B.

During the next movement of the turret which carries the can from station B into station C, the can is brought into engagement with a pair of 25 outer spaced and curved guide bars 22, 23 (Fig. 3) which extend adjacent the turret through stations C, D and E. These bars hold the can in its pocket throughout the remainder of its passage through the machine and until it is 30 fully coated and discharged. At their upper ends the guide bars are mounted on a short shaft 24 which projects from and is carried in a boss 25 formed integrally with the main frame adjacent its top. At their lower ends the guide bars are 35 provided with depending feet 26 which are bolted to a table portion 27 of the main frame. This table extends laterally from the front of the frame and is located under the turret.

At the spraying station C the can is in horizontal alignment with a rotating electromagnetic chuck 31 (Fig. 4) its bottom end being adjacent the face of the chuck. The chuck 31 is mounted on the end of a short hollow horizontal shaft 32 which is carried in a bearing 33 formed in a bracket 34. This bracket is part of a horizontally disposed can slide 35 which has movement in a guideway 36 (Fig. 1) formed in the lower part of the main frame 15 adjacent the table portion 27.

With the can at station C and the turret on its rest period, the slide 35 moves forward and brings the chuck 31 into holding engagement with the bottom of the can, the slide being operated in any suitable manner.

The magnetism of the chuck for holding the can is effected by electrical energy supplied thereto along wires 37 (Fig. 3) which connect with electrical brushes 38 bolted to a shelf 41 formed on the side of the bracket 34. This provides the stationary element. The brushes contact insulated rings 42 which are mounted on the end of and turn with the hollow shaft 32, the rings being adjacent the bearing 33. These rings are electrically connected with the chuck by wires 43 which extend inside of the shaft. This is the 60 movable part of the chuck assembly.

While thus held on the chuck the can is rapidly rotated in its turret pocket 21 in a counter-clockwise direction (Fig. 1). Rotation of the chuck is effected by a gear 45 (Figs. 3 and 5) which is mounted on the shaft 32 just back of the chuck. Gear 45 meshes with and is driven by a gear 46 which is mounted on a drive shaft 47 journaled in a bearing 48 formed in the bracket 34 this being below the bearing 33. The shaft 47 is, therefore, 75

carried by the slide 35 and is continuously rotated in time with the other moving parts of the machine in any suitable manner.

At the front of the turret 11 the open end of the can is disposed in direct axial alignment with a spray head 51 (Figs. 1, 3 and 4) comprising a nozzle 52 and a hollow body 53. The spray body is pivotally mounted on a stud 54 carried in a boss 55 formed on the top of a bracket 56 which extends up from the table 27.

The nozzle is equipped with a suitable needle valve that is operated by compressed air so that when the valve is open a coating material is discharged from the spray head and when closed no spraying takes place. This needle valve may be operated from a pressure cylinder 57 which is directly behind the spray head. The valved, air-controlled spray head herein referred to may be one of several well known constructions and it is believed that for the present purposes further details are unnecessary.

The cylinder 57 is secured to the end of the spray head body and is connected with one end of a compressed air pipe 58 which leads to a needle valve control device 59 graphically indicated in Fig. 6. Here it is shown in its association with an electric circuit used in electrically operating all of the spray heads. This will be fully explained in connection with a description of the wiring diagram of Fig. 6 which will be given later.

The spray head body 53 is connected with the ends of two other pipes 61, 62. Pipe 61 connects with a source of supply of liquid coating material which may be forced under pressure in any suitable manner to deliver it to the nozzle 52. The pipe 62 is a compressed air supply pipe for bringing the air into the nozzle for atomizing and ejecting the coating material therefrom when the valve is open. These are usual features of such spray heads.

While the can is being rapidly rotated with the chuck at station C, the nozzle needle valve is opened and a spray of coating material is projected into the can (Fig. 4) striking against its bottom. During this spraying operation the nozzle is oscillated to cover the entire inner surface of the can bottom its position at the beginning (dot and dash lines Fig. 4) particularly directing the coating into the corner between bottom and side walls as has already been suggested.

The oscillation of the spray head is effected by an arm 65 (Figs. 3 and 4) which is pivoted on the pivot stud 54 and is secured to the head body 53 by a screw 66. The opposite end of the arm connects with a link 67 which in turn is actuated by a suitable moving part of the machine fuller details of which are not necessary for my present purpose.

The flow of spray material is cut off when the spray head is in the full line position of Fig. 4 and any atomized spray or fumes circulating in the air around the nozzle end or in the can after the completion of the spraying operation are carried off through an exhaust duct 68 which surrounds the open end of the can and the nozzle end of the spray head. This duct is secured to the side of the bracket 56 by screws 69 (Fig. 1) and may be connected with any suitable suction means such as an exhaust fan or the like. The same exhaust duct is located at the three stations C, D and E and thus function the same for all spray heads.

The slide 35 and chuck 81 are now drawn back

from the turret and in so doing the outer edge of the bottom of the rotating chuck can engages a stripper plate 71 (Fig. 4) which pulls it off of the chuck and leaves it in its turret pocket. It thereupon stops turning. The stripper plate is secured to the back of the curved guide bar 23 by shouldered bolts 72 and is provided with an opening 73 just a little larger than the chuck but too small for the can to pass through.

The turret on its next step of rotation presents the partially coated or bottom coated can to the spraying station D. Here the can is located between a second rotating electro-magnetic chuck 81 and a second spraying head 82 these being similar to the chuck and spray head of station C just described. The spray head 82, however, is offset from the center of the can as best shown in Fig. 2 and does not oscillate as the head 51.

The rotating chuck 81 is mounted on the forward end of the drive shaft 47 adjacent the gear 46 and is therefore carried on the slide 35. It receives its magnetic energy by way of wires 83 (Figs. 2 and 4) which are disposed inside of the hollow rotating shaft 47 and which connect with insulated rings 84 (Fig. 3). This constitutes the movable element of the chuck assembly.

The rings are electrically engaged by contact brushes 85 which are secured to an insulated block 86 mounted on the top of the slide 35. The brushes are connected to the ends of lead wires 87 coming from a suitable source of electrical power. This brush assembly provides the stationary element of the magnetic control.

The slide 35 moves forward to bring the chuck 81 into holding engagement with the can bottom the chuck passing through an opening 88 cut through the stripper plate 71. The can upon engaging with the rotating chuck rotates therewith, this being in a clockwise direction (Figs. 1 and 5). The spray head 82 is then moved into the can, performing the spraying action (see Fig. 2).

The head 82 is mounted on the top of a bracket 91 and the latter extends up from a dovetail bottom 92 which slides in a guideway 93 formed in the top of the table 27. The bracket is moved toward the can by a horizontal actuating rod 94 one end of which is threadedly engaged with the bottom 92. This rod slides in a bearing 95 of the main frame and is actuated by any suitable moving part of the machine.

The spray head 82, like the spray head 51, is of the compressed air type and comprises a nozzle 97 and a hollow body 98 which is bolted to and carried by the bracket 91. Nozzle 97 projects a stream of coating material toward the front and the outer side of the head and at an angle to the nozzle, this action depositing the coating well into the can corner *d* when the nozzle is first fully inserted into the can (Fig. 2). Discharge of coating material continues during the backward movement of the spray head which immediately follows and it is then that the side wall of the can is fully covered. Since the can rotates the spray is caused to flow well into the edge of the side seam and into the junction of side seam and can wall.

The needle valve of this spray head may also be air operated, as by a pressure cylinder 99. The cylinder 99 is secured to the end of the spray head body and is connected with one end of a compressed air pipe 102 which leads to a needle valve control device 103 also graphically indicated in Fig. 6. The operation of this will be fully

explained hereinafter. The body 98 like the spray head body 82, also has connection with a liquid coating material supply pipe 104 and a compressed air pipe 105.

- 5 The nozzle also sprays the can flange just at the end of the outward or return sliding movement of the bracket 91 and as the spray head is withdrawn from the can. The needle valve is then immediately closed and the spray is cut off by operation of an electric switch controlling through the air cylinder 99. This switch action will be later described in connection with the wiring diagram. The can slide 35 is now drawn back which action pulls back the rotating chuck 15 through the stripper plate opening 88 and this strips off the can leaving it in its turret pocket.

With the next step movement of the turret 11, the can moves into the third spraying station E where its side walls and the bottom joint receive 20 a second coat. The mechanism at this station is identical with that at the station D just described and the operation is the same except that the can is rotated in the opposite direction.

At station E the can is picked up and rotated 25 by a magnetic chuck 111 (Fig. 2) and the coating material is delivered by a spray head 112. The chuck is mounted on the end of a hollow shaft 113 carried in a bearing 114 formed in the bracket 34. It receives its magnetic energy 30 by means of wires disposed in the hollow shaft, of insulated rings mounted on the shaft and by means of brushes supported on the bracket 34 in the same manner, already described, as for the chuck 81. The chuck 111 is rotated in its 35 counter-clockwise direction (Fig. 5) by a gear 117 (see also Fig. 2) which is mounted on the shaft 113 just back of the chuck. This gear 117 meshes with and is driven by the gear 46.

The needle valve compressed air control for 40 the spray head 112 utilizes a pipe 119 (Fig. 1) which connects with a needle valve control device 120 (Fig. 6) and which is associated with a cylinder 121 connected directly with the needle valve of the spray head. The spray head 112 is also 45 associated with a compressed air pipe 122 (Fig. 1) and a liquid coating material pipe 123.

The head 112 is also mounted on the slide bracket 91 adjacent to and parallel with the head 82 and its movement into and out of the can during spraying is therefore in unison with the movement of the head 82. In this second application 50 of coating the spray material is again directed into the corner *d* of the can and again the can flange is sprayed as the nozzle is withdrawn this being in addition to the side wall coating as already described.

By reason of the opposite direction of rotation of the can the other edge of the side seam and the junction between this edge and the can 55 side wall is thoroughly coated this being one of the vulnerable parts of the can as previously pointed out. At the same time the third coat of material is applied to the corner *d* which is another vulnerable part.

60 At the next step rotation of the turret the can is carried beyond the end of its supporting guides 22, 23 and drops out of its turret pocket and into a discharge chute. The discharge chute comprises spaced and parallel angle iron bars 125 disposed on each side of the turret adjacent the station E. At the rear of the turret the bars are bolted to a boss 126 (Fig. 5) formed on the main frame 15. At the front of the turret they are bolted to a bracket 127 (Figs. 1 and 2) which is 65 supported by and secured to the table 27. The

bracket 127 also supports an end of the exhaust duct 68. The bars 125 are disposed at an angle and the cans roll by gravity out of the machine and to any suitable place of deposit.

A no-can-no-spray device best illustrated in 5 Figs. 5 and 6 is associated with each of the spraying stations C, D and E. In each device rocker detecting members are mechanically actuated by the can at a station and when so actuated open and close electric circuits which function to control the compressed air and the coating material discharged from the spray head. The control devices 59, 103 and 120 are selectively utilized at such a time so that the coating material is sprayed into the can at the proper time and 10 only when a can is present and properly placed 15 at a station.

The rocker detecting members at the respective stations C, D and E comprise bell cranks 131, 132, 133 which are pivotally mounted on the 20 shoulder studs 72 between the stripper plate 71 and the guide rail 23 (Figs. 3 and 4). One arm of each bell crank normally extends into the path of travel of the can as advanced by the turret 11. The other arm of each bell crank engages a 25 spring held movable part of a normally open electric switch.

These electric switches, designated by the numerals 135, 136, 137, (Figs. 5 and 6) are of any suitable construction, many types of commercial 30 switches now being available. It is the spring element of each switch which holds the associated crank arm in the path of travel of the can. The switches 135, 136 of stations C and D are secured to lug extensions 138, 139 (Figs. 1 and 5) 35 which are formed as a part of the guide rail 23. The switch 137 of station E is secured to a boss 25 formed on the table 27 of the main frame 15.

Reference should now be had to the wiring diagram of Fig. 6. The switches 135, 136, 137 form 40 part of a plurality of normally open electric circuits which include the needle valve control devices 59, 103, 120. Electric current is supplied to the circuits from a generator 151 one side of which is connected by a wire 152 to one terminal 45 of a service switch 153. The other side of the generator is connected to the opposite side of the service switch by a wire 154. The service switch when closed connects the wire 152 with a main service wire 155 and the wire 154 with a 50 return service wire 156.

The return service wire 156 connects with one terminal of a timing switch 157 which is closed 55 only when the turret 11 is stationary. This switch actuation is performed by a cam 158 which is mounted on a continuously rotating shaft 159 suitably actuated from a moving part of the machine and in synchronism with the turret movement.

The other terminal of the timing switch 157 60 connects with one end of a service wire 161. Lead wires 162, 163, 164 respectively connect this service wire with the needle valve control devices 59, 103, 120. Wires 166, 167, 168 respectively connect the devices 59, 103, 120 with the switches 65 135, 136, 137.

With the service switch 153 closed a can coming into any one of the spraying stations and moving the bell crank there closes its associated electric switch and when the turret comes to rest 70 and closes the timing switch 157 an electric circuit is completed through the particular needle valve control device associated with that electric switch.

For example a can at station C has moved the 75

bell crank 131 so that the switch 135 is closed. Electric current now passes from the generator 151 along the service wire 152, switch 153, wire 155 which connects with one side of the switch 135, through the switch 135, along wire 166, through the needle valve control device 59, along wires 162, 161, timing switch 157 and wires 156, 154, through the service switch back to the generator. This actuates the needle valve control device 59 which opens an air valve and permits air to pass from a main supply pipe 169, which connects with all of the needle valve control devices, through the pipe 58 into the cylinder 57. This moves the needle valve stem and opens the needle valve in the nozzle so that a spray of liquid coating material flows through the pipe 61 and air flows through the pipe 62 and the mixture is ejected from the nozzle and into the can.

In like manner a can introduced into station D or station E closes its particular switch 136 or 137 and establishes a circuit which actuates its needle valve control device 103 or 120 to open the needle valve of that particular spray head. The service wire 155 is connected by a wire 171 to the switch 136 and a wire 172 similarly connects the service wire 155 with the switch 137.

When the needle valve control device 103 is actuated, therefore, the current passes from the service wire 155 by way of wire 171, switch 136 and wire 167, through the device and its wire 163 and back to the service wire 161. Otherwise the rest of the circuit is the same as already described for the device 59. Where the switch 137 at station E is closed, the current then flows from service wire 155 by way of wire 172, switch 137 and wire 168, through the device 120 and its wire 164 and back to the service wire 161.

It will be evident, since each spray head is controlled by its own circuit which is only closed by a can in proper position to be sprayed at each spraying station, that all of the circuits may be closed simultaneously if there is a can at each station. By the same token if there is no can in a particular turret pocket at a spraying station the detecting rocker member there will not be actuated and no spraying will take place at that particular station.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A spraying machine for coating cans with a liquid coating material comprising in combination, means for carrying open-end cans intermittently and successively through a plurality of spraying stations, means for rotating individual cans while at said stations, an oscillating spraying device at one of said stations for coating the interior surface of the bottom of a said rotating can through its open end, means for changing the angle of said spraying device relative to the bottom of said can, a plurality of reciprocating spraying devices at the other of said stations for successively applying a plurality of coats of said coating material to the interior side wall of said cans, and means for moving said reciprocating spraying devices into and out of said cans through their open ends.

2. A spraying machine for coating cans with a

liquid coating material comprising in combination, means for successively positioning open-end cans, having inwardly projecting side seams, at a plurality of spraying stations, means associated with each of said stations for ejecting a spray of said coating material at an angle to strike against a longitudinal edge of said side seam and against the interior side wall of a said positioned can, a chuck arranged at each of said stations for rotating the positioned can about its longitudinal axis while it is being sprayed, and means for revolving said chucks in opposite directions relative to each other, and means for moving the can from one to the other of said chucks, so that said spray is directed against opposite longitudinal edges of said side seam and into the interstice between the edges of the side seam and the can side wall.

3. A spraying machine for coating cans with a liquid coating material comprising in combination, means for carrying cans successively through a plurality of spraying stations, a rotatable magnetic chuck associated with each of said stations for revolving said cans, means for moving said chucks into engagement with and away from said cans while they are in said carrying means, and a stripper plate for removing a said engaged can from a said chuck to maintain said can in said carrying means.

4. A spraying machine for coating cans with a liquid coating material, comprising an intermittent can carrier, a rotary chuck to which the cans are delivered by said carrier at its intermittent, and a plurality of spraying devices for successively coating, independently of each other, different interior surfaces of a can, one of said spraying devices being movable within the can relative to the axis of the can for insuring a complete interior coating.

5. A spraying machine for coating cans with a liquid coating material, comprising in combination, means for positioning open-end cans for coating, independent spraying devices for successively coating different interior surfaces of the positioned can, one of said spraying devices being movable within the can relative to the axis of the can for insuring a complete interior coating, and means for moving the cans from one spraying device to another spraying device, and means for inserting the spraying devices into the cans.

6. A spraying machine for coating cans with a liquid coating material, comprising in combination, means for individually presenting open-end cans in spray receiving position, means for rotating a positioned can, automatically acting spraying means for coating different interior surfaces of said positioned cans, independently of each other, one of said spraying means being movable within the can relative to the axis of the can, and means for conveying the cans from one spraying means to another spraying means, and means for inserting the spraying means into the cans.

7. A spraying machine for coating cans with a liquid coating material, comprising in combination, means for intermittently carrying open-end cans successively through a plurality of spraying stations, can rotating means at said stations, automatically acting spraying means associated with each of said stations for coating different surfaces of a said can progressively, one of said spraying means being movable within the can relative to the axis of the can, and devices for inserting the spraying means into the cans.

8. A spraying machine for coating cans with a

- liquid coating material comprising in combination, means for intermittently and successively positioning open-end cans at a plurality of spraying stations in spray receiving position, magnetic chucks at each of said stations for rotating said positioned cans, automatically acting spraying means associated with each of said stations for progressively coating different surfaces of said positioned cans while rotating at said stations, 5 one of said spraying means being movable within the can relative to the axis of the can, and devices for inserting the spraying means into the cans.
9. A spraying machine for coating cans with a liquid coating material comprising in combination, an intermittently rotary turret for positioning open-end cans in spray receiving position, chucks for receiving and rotating said cans in the intermissions of said turret, an oscillatable spraying device for spraying the interior surface of the bottom of a positioned can through its open end, means for oscillating said spraying device so as to direct the spray against a desired portion of said bottom surface, a reciprocable spraying device for spraying the interior surface of the side wall of said positioned can independently of said bottom, and means for moving said reciprocable spraying device into and out of the interior of said can through its open end, said 20 spraying devices being arranged at different stations of said turret.
10. A spraying machine for coating cans with a liquid coating material comprising in combination, means for successively rotating a can about its longitudinal axis in opposite directions, including chucks rotated in opposite directions and means for moving the can from one chuck to the other, spraying means for successively coating the interior surface of said can while it is so 25 rotating, said means for moving a can from one of said chucks to the other chuck being intermittent.
11. A spraying machine for coating cans with a liquid coating material comprising in combination, means for placing open-end cans in spray receiving position, means for successively rotating a positioned can about its longitudinal axis in opposite directions, including chucks rotated in opposite directions and means for moving the can 30 from one chuck to the other, spraying means for successively coating the interior surface of a said positioned can while so rotating, said means for moving a can from one of said chucks to the other chuck being intermittent.
12. A spraying machine for coating cans with a liquid coating material comprising in combination, means for rotating a can having an inwardly projecting side seam intermittently in opposite directions about its longitudinal axis, a can feeder for feeding cans intermittently to said rotating means, and spraying devices disposed out of alignment with the longitudinal axis of said rotating can and insertable therein for ejecting and directing coating material at an angle to 35 and against the side walls of said can for coating the same and for coating the longitudinal side seam edges and the interstices between said edges and the can wall.
13. A spraying machine for coating cans with a liquid coating material comprising in combination, an intermittently movable can carrier for positioning open-end cans having inwardly projecting side seams in spray receiving position, devices for ejecting a spray of said coating material 40 at an angle to and against the interior side walls of said can, and means for rotating a said can about its longitudinal axis first in one direction and then in the opposite direction while the can is being sprayed, including chucks rotated in opposite directions and means for moving the can 45 from one chuck to the other so that the side walls, the edges of the side seam and the interstices between the said edges and the can wall are thoroughly covered with said material.
14. A spraying machine for coating cans with liquid coating material, comprising in combination a continuously rotating chuck turning in one direction for presenting open-end cans in spray receiving position, a succeeding chuck for said purpose and turning continuously in the opposite direction, spraying means for independently coating different interior surfaces of a said positioned can, an intermittently turning can feeding turret for delivering cans successively to said chucks, and controlling means associated with said spraying means for automatically controlling the time and duration of said coating operations.
15. A spraying machine for coating cans with a liquid coating material comprising in combination an intermittently turning can-feeding turret, a continuously rotating chuck for receiving cans from said turret, a succeeding chuck turning continuously in the opposite direction to receive cans transferred by said turret from said first chuck, said devices presenting open-end cans in spray receiving position, spraying means for independently coating different interior surfaces of a said positioned can, and means operable by a said positioned can for electrically actuating said spraying means.
16. A spraying machine for coating cans with a liquid coating material, comprising in combination, a can feeding turret and can rotating chucks for presenting open-end cans in spray receiving position, a plurality of independent spraying means for coating different surfaces of a said positioned can, one of said spraying means having devices for inclining the axis of the same relative to the axis of the can, while the spraying means is within the can, means operable by a said positioned can for electrically actuating said spraying means, and controlling means associated with said spraying means for controlling the time and duration of said operation.
17. A spraying machine for coating cans with a liquid coating material comprising in combination, an intermittently movable turret, means independent of the turret for successively rotating a positioned can about its longitudinal axis in opposite directions, including chucks rotated in opposite directions and means for moving the cans from one chuck to the other, and spraying means for applying a coat of said material at the juncture of the can end with the can side wall of a positioned rotating can while the can is being rotated by each chuck.
18. In a can-spraying machine, the combination of an intermittently movable can carrier, rotatable chucks to which the cans are successively delivered by said carrier, means for rotating said chucks continuously in opposite directions, and means near said chucks and insertible into the cans for spraying the interiors of the rotating cans.
19. In a can spraying machine the combination of an intermittently rotary can carrier, chucks rotating in different directions to which chucks the cans are successively delivered at the intermissions of said carrier to be rotated for limited times, first in one direction and then in another

direction, spraying means at one chuck for operating on certain parts of a can, and spraying means at another chuck for operating on other parts of the can.

5 20. In a can spraying machine the combination of an intermittently rotary can carrier, a chuck rotating in one direction to which chuck the can is delivered by said carrier, spraying

means for operating on the can while it is rotated by said chuck, another chuck rotating in another direction to which the can is delivered by said carrier after said spraying operation, and spraying means at said other chuck for operating on said can. 5

JOHN H. MURCH.
